(57) **CLAIM**

The ornamental design for a personal watercraft hood, as shown and described.

DESCRIPTION

FIG. 1 is a front left perspective view showing a personal watercraft hood according to my design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof; and,

FIG. 8 is a reduced front left perspective view thereof on a personal watercraft, with the personal watercraft shown in broken lines.

The broken lines in FIG. 8 show unclaimed structure or environment, are for illustrative purposes only and form no part of the claimed design. In FIGS. 3 and 5, the dotted/dashed lines immediately adjacent solid lines represent unclaimed boundaries of the claimed design and as such, the configuration of the unshaded surfaces defined by those dotted/dashed lines form no part of the claimed design.
